EXPLOSIVE PROJECTILE

Salamon Lebensart, Vienna, Austria

Application January 4, 1933, Serial No. 650,167
In Austria January 8, 1932

34 Claims. (Cl. 102—29)

The invention refers to explosive projectiles or shells with percussion fuses, particularly with so-called "direct" acting percussion fuses, in which, when the shell strikes, the ignition organs are actuated by forces of inertia and not by the force of a spring, and the invention is particularly suitable for shells which are thrown by hand, or in some other primitive way as, for example, from the barrel of a throwing device the barrel of which is not provided with rifling.

For securing the fuse during storage, transport and throwing, shells are often provided with a safety pin device, the safety pin of which projects from the shell through at least one external opening to the outside. The invention particularly concerns this type of safety device. With this safety device it is very important to provide for a reliable withdrawing movement of the safety pin, particularly when this is to take place during the flight of the shell and to give particular attention to the proper sealing of the exit openings of the said pin. The invention does this in a particularly advantageous manner.

The elements, namely, the shell, the fuse chamber, the fuse movably mounted in the fuse chamber and the safety pin, if this is provided, have hitherto been built in such relative positions which were either co-axial, parallel-axial, or perpendicular to one another. With the shell according to this invention, however, by using a fuse which can assume positions in the fuse chamber either in axial direction or parallel to the axis, or even in slanting direction, at least two of the elements mentioned, or at least two of their axes, are in slanting relative positions (thus not in co-axial, parallel, or perpendicular relative positions) when the shell is ready for use, or even also when ready for throwing or in flight. When the shell has been made ready for throwing, according to the invention the said oblique or diagonal position may either remain, or may be changed into a parallel or perpendicular relative position of the elements mentioned (so far as these are movable).

The invention also attains the same object through the single exit opening provided for the pin being arranged in a suitable position in the base or cover of the projectile and advantageously in an oblique position, and the arrangement of the exit opening for the safety pin is preferably combined with the oblique relative position of the elements mentioned above.

If, during the projection of the shell, the safety pin device is held externally in the safety position, it then forms an "external" projection safety

device. It may accidentally happen, however, that this "external" projection safety device becomes released during the actual projection. The fuse, particularly a "direct" percussion fuse, may then cause a premature explosion during the actual projection due to the forces of inertia set up by the projection itself. In order to avoid this defect, according to the invention, in addition to the "external" projection safety device mentioned, a second parallel-acting "internal" projection safety device is provided which releases itself automatically during flight.

Shells projected in the primitive manner mentioned, particularly hand grenades, frequently tumble and rotate considerably during flight. Centrifugal forces are thereby produced. These may even become so great as to ignite released shells during flight, thus causing explosions in the air. The invention overcomes these disadvantages also by providing a special "centrifugal force safety device", i. e., a safety device which holds the fuse in the safety position should centrifugal forces occur which are too great and which could cause ignition. In addition, according to the invention, with the same object, against the ignition movement supplementary mechanical, preferably spring or elastic resistances are inserted, the said resistances being of such a magnitude that even the greatest centrifugal force which could occur in practice cannot cause ignition, even when the ignition of the fuse parts has already been released. These two latter provisions ensure in general that, not only is danger from the centrifugal force overcome, but in fact all dynamic forces acting in a direction to cause ignition, and which are so large that they might lead to an explosion, become harmless.

The invention is shown diagrammatically in the drawing and, for example, as applied to a hand grenade having a "direct" percussion fuse, which is secured by a pin-like element passing through the fuse.

All the figures show diagrammatically longitudinal cross-sections, the relative functioning positions of the fuse parts being shown in Fig. 1 during transport, in Fig. 2 during flight, in Fig. 3 after the ignition elements have finished their ignition movement, and in Fig. 4 in the case where the "centrifugal force safety device", or the "internal" projection safety device, provided according to the invention, has not been released, either in flight or as a result of a centrifugal force or striking force of such magnitude which might be dangerous.

In the drawing T is the shell, X the shell cas-

ing, Z the fuse casing attached to X by screw threads, for example, M the fuse chamber having concave upper and lower guiding surfaces Z₁ and Z₂ for a "direct" percussion fuse P, the guiding surface Z₁ forming at the same time the cover of the fuse casing Z.

A and B are the two parts of the fuse P which carry the ignition means a and b, the inner part A and the outer B also acting as inertia masses which cause ignition in any direction of impact by subjecting the said parts A and B to a telescopic displacement relative to each other thereby approaching the ignition means a and b to each other.

C is a spring ring capable of performing a rolling movement and containing advantageously one or more rigid parts. The said spring ring constantly tends to shrink together to a smaller diameter and forms, at the same time, both the safety devices according to the invention, namely the "internal" projection safety device and the "centrifugal force safety device", as well as fulfilling, in accordance with the invention, still other functions as will be described.

The fuse P, having its axis on the line u—z, of Fig. 1, is mounted obliquely or diagonally in the fuse chamber M and the shell T, respectively.

The fuse is held in the "safe" position by the pin E which passes diagonally through it and the shell; the said pin E preferably constituting a cotter pin which crosses and bores or passes through the entire fuse P and does not simply lie between the fuse parts A and B, the cotter or spring effect of the said pin E increasing the safety to be attained. The cotter E passes out from the fuse chamber M and the shell T through the opening R provided in the cover Z₁.

The exit opening R is sealed by a sealing ring F. A spring H acts on a plate I carried on the cotter E, and tends to move the cotter E outwards. With the method of support thus provided at one end, or at one point, the cotter E can swing in the opening R about the point of support, and the fuse P can also move with it so far as it has play in the fuse chamber M. This movement will be somewhat limited at the point of support of the cotter E by elastic parts (sealing ring and spring) provided at R. When the shell is severely shaken or jolted in its safe condition, the said freedom of movement of the fuse has a good effect as the parts are less subject to the danger of being deformed by the stresses provoked by shaking during transport.

The diagonal arrangement of the safety cotter pin E makes it possible, even with an axial fuse chamber M, to provide the exit opening R on the cover Z₁ of the said fuse chamber M, and to there arrange sealing and safety devices. Otherwise the exit opening with an axial fuse and axial fuse chamber ultimately will lie on the side wall of the fuse or shell where there is a lack of space for arranging this device, where centrifugal forces often have an unfavourable direction relative to the direction of forces acting to automatically release the safety device, and where the safety lever K cannot easily be arranged to give equally good effect, and where an equally good sealing cannot be attained. These advantages could certainly be partly obtained by arranging, in a known manner, the fuse chamber, together with the fuse, perpendicular to the axis of the shell and arranging the safety pin device directly axially, but the transmission of the fire from the fuse to the explosive filling 75 the shell T would then be unsatisfactory, par-

ticularly in the case of fuses in which the free path of the inertia masses A, B is great as will be explained.

The lever K which is firmly held (but releasable) against the shell by suitable means, for example, a wire S shown diagrammatically, when in its initial position as shown in Fig. 1 opposes the action of the spring H, which acts on the lever K in the direction of release. In addition, the lever K transmits its pressure to the sealing ring F with a powerful leverage and this results in a good sealing. The wire clip S gives the shell the necessary safety in transport. The shell only becomes ready for throwing when, by releasing the clip S, the rotation of the lever K about its pivot K₁ is made possible. The cotter pin E can then move outwards during flight, that is when the shell T or lever K is released from the hand holding it or from the gun barrel.

In the constructional example shown both the cotter pin E and the lever K are moved outwards not only by the spring H but also by centrifugal or other inertia forces. The action of the centrifugal force is made more favourable by the cotter pin moving outwards in a direction in which, in the flying shell, there is always a component of the centrifugal force acting generally axially or perpendicularly to the axis of the shell.

The spring ring C forms the safety element and provides at the same time the spring action for the "internal" projection safety device and for the "centrifugal force safety device", owing to its being placed between the surfaces A₁ and B₁ of the fuse parts A and B, thereby preventing the ignition movement when it is in the position shown in Fig. 1 and Fig. 2, thus securing the fuse. Owing to its arrangement it tends to move out of this position on a cone A₂, but is at first prevented from this by the cotter pin E (Fig. 1), which itself passes through both fuse parts A and B, thereby holding these two fuse parts as well as the spring ring C in the position shown in Fig. 1. If this cotter pin E which forms the inwardly projecting positive safety organ of the "external" safety device, falls out, the spring ring C then moves, owing to its own force, generally immediately, as far as the "flying position" shown in Fig. 2, whereby it comes to rest on a cone A₃ or A₄ or between these two, and then assumes the action of a repulsion spring.

As can be seen from the drawing, the guides controlling the movement of the rolling spring ring are formed in several sections. According to the example shown on the drawing the three cones are made with various degrees of angularity, namely, the cone A₂, which is intended for the initial position of the spring ring C (and therefore has the greatest diameter) is made the flattest, the cone A₄ (which has the smallest diameter) is made the steepest, and the cone A₃ (which is inserted between them) has a medium steepness. The transition from one cone to the other may be suitably made through one or more small steps.

The handling and working of the grenade shown is as follows:—

During storage and transport the hand grenade carries the safety device or clip S (Fig. 1). Before projection or throwing, the safety device S is released. After this safety device S has been released, the lever K must be held by the hand or the gun barrel in the position shown in Fig. 1, and thereby the positively acting "internal" safety pin E of the "external" projection safety device is held in its safety position. At the

commencement of flight the "external" projection safety device K and E is released and the cotter pin E leaves the fuse chamber M. If the projectile takes its normal course the spring ring 5 C goes into its "flying position" as shown in Fig. 1, and the fuse which, as shown in Fig. 1, was inserted in a diagonal initial position, thereby, under the action of the spring ring C or of the centrifugal force in the tumbling or rotating shell, 10 leaves its slanting initial position thus taking up a position which with reference to the ignition chamber M is more axially directed (Fig. 2). In this way the disadvantage of the fuse becoming fixed in the position in which it is originally inserted (and for this reason functioning incorrectly) is overcome, which disadvantage is otherwise particularly observable in the case, for example, of shells which have been stored for a long time.

20 If the removal of the cotter pin E takes place during an acceleration or delay period, for example, out of proper order during projection, the inertia forces of the parts A and B caused by the projection, act in opposition to the force of the 25 spring ring C in the position shown in Fig. 4, and and thereby prevent the release of the fuse. Owing to the parts A and B being mounted between concave surfaces Z₁ and Z₂, this effect occurs in every direction of the accelerating force. Consequently, even if the "external" projection safety device K and E is accidentally released during projection, the fuse is still further protected by the "internal" projection safety device C and is only 30 released (to enable ignition) during actual flight and not during projection. In addition, owing to the special automatic "internal" projection safety device C, the complete release of the fuse can only take place after the completion of the acceleration period, i. e. during the free flight, 35 even if the release of the "external" projection safety device should have been completed earlier, that is, during the acceleration period.

As can be seen from Fig. 1, the "internal" projection safety device C is necessarily or positively held in its safety position by the "external" projection safety device K and E both during projection and also during transport.

The spring ring C also forms, in its position shown in Fig. 4, a "centrifugal force safety device". If, for instance, the "external" projection safety device K and E is released during flight and thus releases the action of the spring ring C, as well as the free play of the centrifugal force, the spring ring C does not leave its safety position 55 (Fig. 4) if the centrifugal force is so great that it could cause ignition in the flying position of the fuse parts (Fig. 2). In such a case the centrifugal force, acting against the spring ring C, prevents it from leaving the position of Fig. 4, in which the 60 spring ring C actually forms the safety element, as it prevents a telescopic relative displacement of the parts A and B sufficient to cause ignition, that is, it prevents the needle a from penetrating into the fuse cap b. With the construction of the 65 grenade shown in the drawing, or with the arrangement of the fuse P in the fuse chamber M as shown the centrifugal force acts quite independently of whatever axis the grenade is rotating or tumbling about, and thus independently 70 of how the centrifugal force is directed relative to the axis of the shell. Accordingly the centrifugal force acts constantly so that, on the one side, the two fuse parts A and B, as well as the ignition means a and b tend to move towards one 75 another in the direction necessary to provoke igni-

tion, or are forced against one another, and that, on the other side, the spring ring C is hindered in its action or prevented from acting. In addition, the spring ring C when in its flying position, as in Fig. 2, that is, in its position in the translation stage from cone A₄ to cone A₃, offers a greater resistance to any centrifugal force which may occur than when in its position on the steeper cone A₄, and the spring ring C thereby also prevents any damaging effect of the centrifugal force if this is so great as to become dangerous, by bringing about an explosion in the air.

On impact, for instance with the target or generally the ground, the fuse, which has been released as shown in Fig. 2, takes up the position shown in Fig. 3, in which the striking pin a has penetrated the percussion cap b and, owing to the universally movable guiding of the fuse parts A and B carrying the ignition means a and b between conical surfaces Z₁ and Z₂. This ignition movement occurs with any relative striking direction of the grenade. The free path of the parts A and B carrying the ignition means, that is the path through which these parts A and B must pass in order to bring the tip of the pin a into contact with the surface of the percussion cap b, is abnormally large, i. e. a minimum of 4.5 mm. but preferably not more than 15 mm., in order to ensure certain ignition, and thus high sensitivity, also when striking on soft ground, for example, long grass or snow. The diagonal arrangement described is particularly suitable for the application of such an advantageous, abnormally great free path.

The invention is particularly suitable for 35 grenades having "direct" percussion fuses, as shown in the drawing, because then the inertia of the same fuse parts A and B, which serve during projection to hold the "internal" safety device C, can also be utilized not only to effect ignition on impact through their inertia, but also to supply the "centrifugal force safety device" which is necessary in the case of large dangerous centrifugal forces.

As can be seen from Fig. 1, the "external" and 45 "internal" projection safety device, or the "centrifugal force safety device" (according to the invention at least one of these) does not come in the safety position but during the working of the fuse is initially built in the said actual and 50 positive safety position so that the said projection safety devices also protect the grenade during transport etc.

The invention may also be carried out in a 55 manner which varies in many ways from the constructional example shown in the drawing.

The cotter pin E, for example, may be positively connected with the lever K in any manner desired, for instance, by wire or chain, and either firmly or loosely. A spiral spring for tension 60 and pressure may be arranged, for example, between the plate I of the cotter pin E and the lever K, whose ends are firmly connected to the pin plate I and the lever K, respectively. When the safety device S has been released this spring 65 then forces, first of all, the lever K away from the shell and, at the same time, presses in the cotter pin E in an inward direction holding it for some time in its safety position. Thus, the outward movement of the cotter pin E can only begin when the pressure effect of this "connecting spring" is sufficiently reduced. In this construction the "connection spring" will, in general, be placed under tension under the influence of the lever K, and in its outward movement takes the 70 75

cotter pin E with it. The "connection spring", which is not shown in the drawing may also form a part of the "releasing spring" H, correspondingly projecting above the plate I.

5 Apart from the safety devices shown, the fuse may, for example, also contain in addition suitable locking devices, which, for instance, render the fuse harmless in the case of a misfire or accidental dropping, such as are described, 10 for example, in the applicant's earlier U. S. Patents No. 1,709,798 and No. 1,769,848 in connection with a spring ring C and two telescopic fuse member carriers A and B.

In the construction shown on the drawing the 15 "external" safety device K and E achieves the desired object to give safety during throwing or projection in itself, without a separate "internal" safety device C, and conversely the "internal" projection safety device C could also be constructed 20 in such way (for example in accordance with the previously mentioned earlier patents) as to achieve the object of giving complete safety during projection in itself, i. e. even in the case when the lever K of the "external" safety device 25 is released before throwing or projection.

According to the invention the cotter pin E may be held in its safety position during throwing or projection (Fig. 1) by forces of inertia, and in this connection the cotter pin E may be 30 made with small notches, grooves, or the like in which the fuse parts A and B engage.

The fuse chamber M may vary from the constructional example shown in the drawing by having its axis x—y not parallel to the axis of 35 the shell, but, instead, being arranged in such a way that the axis of the fuse chamber is diagonal to the axis of the shell.

The diagonal arrangement of the cotter pin E may also be used when the fuse P is built in axially, but by having the fuse built in diagonally also, the diagonal arrangement of the cotter pin E is simplified from the point of view of construction.

In order to have the exit opening R on the 45 cover Z₁ of the fuse casing, the cotter pin E can, if required, be made somewhat bent, which may also be advantageous for releasing the safety device.

By the word "cone", mentioned herein, is not 50 only meant a geometrically accurate section of a cone, but one in which the "cone" may run more or less concave or convex. Grooves may be provided if required between the cones or at the ends thereof, into which the spring ring C 55 can snap for the purpose, for instance, of reciprocally locking the carriers A and B, in a blind grenade or a grenade striking the ground.

I claim as my invention:

1. An explosive projectile, particularly a hand 60 grenade, comprising a casing having a chamber therein, a universally adjustable fuse in said chamber having ignition and inertia means, a safety device in said chamber for preventing ignition during throwing or projecting, and means associated with the casing and the fuse to maintain the fuse in an oblique initial position in the chamber before throwing or projecting.

2. An explosive projectile, particularly a hand 70 grenade, according to claim 1, in which the means associated with the casing includes a safety pin mounted obliquely through the fuse.

3. An explosive projectile, particularly a hand 75 grenade, according to claim 1, in which the means associated with the casing includes a cotter pin mounted obliquely through the fuse.

4. An explosive projectile, particularly a hand grenade, comprising a casing having a chamber therein, a universally adjustable fuse in said chamber having ignition and inertia means, a safety pin mounted obliquely through the fuse to 5 maintain the fuse in inoperative position in the chamber, said pin being held by the casing in a flexible swingable position, and means to maintain the pin in the chamber and the fuse until the projectile is thrown or projected when the 10 pin is released to permit the fuse to adjust itself and to ignite the projectile on impact by the forces of inertia acting on the inertia means.

5. An explosive projectile, particularly a hand 15 grenade, according to claim 4, in which the pin is swingably mounted within desired elastic limits.

6. An explosive projectile, particularly a hand 20 grenade, according to claim 4, in which the means to maintain the pin in the chamber and fuse includes a lever pivotally mounted on the casing.

7. An explosive projectile, particularly a hand 25 grenade, according to claim 4, in which the means to maintain the pin in the chamber and fuse consists of a lever pivotally mounted on the casing and a removable spring clip to maintain the lever in position to hold the pin in place, said spring clip wholly encircling said casing to enable its release at any point of the circumference 30 of the casing.

8. An explosive projectile, particularly a hand 35 grenade, according to claim 4, in which the means to maintain the pin in the chamber and the fuse includes a lever pivotally mounted on the casing and contacting with the pin, and in which a compression spring is mounted around the pin between the casing and the end of the pin which contacts with the lever so that the spring will force the pin out of the fuse when the lever is released.

9. An explosive projectile, particularly a hand 45 grenade, comprising a casing having a chamber therein, a universally adjustable fuse in said chamber having ignition and inertia means, a safety pin mounted into the casing and through 50 the fuse to maintain the fuse in an oblique initial position in said chamber before throwing or projecting, a lever pivotally mounted on the casing to maintain the pin in position in the chamber and the fuse, and means on the pin to force the pin out of the fuse upon release of the lever when the projectile is thrown or projected so that the fuse may adjust itself during flight to be prepared on impact of the projectile to ignite the fuse by the inertia means.

10. An explosive projectile, particularly a hand 55 grenade, according to claim 9, in which the means on the pin includes a spring pressing against the casing and the end of the pin.

11. An explosive projectile, particularly a hand 60 grenade, according to claim 9, in which the means on the pin includes a spring pressing against the casing and the end of the pin, and in which a sealing ring is provided around the pin and around which the spring is provided to seal the 65 opening in the casing for the pin.

12. An explosive projectile, particularly a hand 70 grenade, comprising a casing having a chamber therein, a fuse in said chamber having ignition and inertia means, a safety pin mounted diagonally into the casing and through the fuse to maintain the fuse in inoperative position in the chamber, a safety device mounted externally of the casing to maintain the pin in place within the casing and fuse, and an internal safety device 75

in the fuse adapted to be automatically released during the flight of the projectile to permit the inertia means to operate on impact.

13. An explosive projectile according to claim 5 12, in which the internal safety device is in the form of a circular spring.

14. An explosive projectile, particularly a hand grenade, comprising a casing having a chamber therein; a fuse in said chamber comprising inner 10 and outer parts, the inner part being movable in the outer part, ignition means provided in the outer part, and means on the casing cooperating with the two parts to force them into a position to fire the fuse on impact of the projectile; and 15 means for maintaining the fuse in the said chamber in an oblique inoperative position until the projectile is thrown or projected.

15. An explosive projectile, particularly a hand grenade, according to claim 14, in which the last-20 named means comprises a circular spring surrounding the inner part, the said circular spring being mounted in its initial position directly onto the said inner part and between the two parts and the force of said circular spring acting 25 against the direction of the firing movement of said two parts.

16. An explosive projectile, particularly a hand grenade, according to claim 14, in which the inner part is provided with a plurality of cone-shaped surfaces, and in which the means on the inner part is in the form of a circular spring surrounding the inner part and contacting with the cone-shaped surfaces.

17. An explosive projectile, particularly a hand grenade, according to claim 14, in which the last-named means comprises a safety pin arranged diagonally into and through the casing, into the chamber and extending through the two parts 40 of the fuse to hold said parts in inoperative position.

18. An explosive projectile, particularly a hand grenade, according to claim 14, in which the last-named means comprises a safety pin arranged diagonally into and through the casing, into the chamber and extending through the two parts of the fuse to hold said parts in inoperative position, and in which a lever is pivotally mounted on the casing to hold the safety pin in position.

19. An explosive projectile, particularly a hand grenade, according to claim 14, in which the casing part which forms the chamber has two oppositely disposed upper and lower guiding surfaces for the fuse.

20. An explosive projectile, particularly a hand grenade, according to claim 14, in which the inner part carries a firing pin so that upon impact of the projectile the inner part will be forced into the outer part whereby the pin will enter the ignition means to fire the projectile.

21. An explosive projectile, particularly a hand grenade, according to claim 14, in which the inner part has a cone-shaped surface, and in which the means on the inner part is in the form of a circular spring surrounding the inner part on the cone-shaped surface, and due to the cone shape the spring will force and maintain the two parts inoperative during flight until the projectile strikes an object.

22. An explosive projectile, particularly a hand grenade, according to claim 14, in which the inner part has three cone-shaped surfaces of different angularity, and in which the means on the inner part is in the form of a circular spring 75 surrounding the inner part on the surfaces, and

due to the cone-shaped surfaces on which the spring slides the spring will force and maintain the two parts inoperative during flight until the projectile strikes an object.

23. An explosive projectile, particularly a hand grenade, comprising a casing having a chamber therein, a universally adjustable fuse in said chamber having ignition and inertia means, a safety device in said chamber for preventing ignition during throwing or projecting, and a safety 10 pin mounted obliquely through the fuse to maintain it in an inoperative position in the said chamber before throwing or projecting.

24. An explosive projectile according to claim 1, in which a spring is provided within the said 15 chamber associated with the fuse and tending to adjust the said fuse from its initial oblique position into a co-axial position with the said chamber after the said safety device is released.

25. An explosive projectile according to claim 1, in which a spring is provided within the said 20 chamber associated with the fuse and tending to adjust the said fuse from its initial oblique position into a co-axial position with the said chamber after the said safety device is released 25 and in which the said spring is inserted into the fuse to constitute a safety means preventing ignition before and during throwing or projecting.

26. An explosive projectile according to claim 1, in which a spring is provided within the said 30 chamber associated with the fuse and tending to adjust the said fuse from its initial oblique position into a co-axial position with the said chamber after the said safety device is released, and said spring also constituting a centrifugal 35 force safety device which opposes the action of the spring to prevent explosion of the projectile in the air.

27. An explosive projectile according to claim 1, in which a helical spring is provided within 40 the said chamber associated with the fuse and tending to adjust the said fuse from its initial oblique position into a co-axial position with the said chamber after the said safety device is released.

28. An explosive projectile according to claim 1, in which a spring is provided within the said 50 chamber associated with the fuse and tending to adjust the said fuse from its initial oblique position into a co-axial position with the said chamber after the said safety device is released, and in which a member is provided as a part 55 of the fuse which has a cone-shaped section cooperating with the spring.

29. An explosive projectile, particularly a hand grenade, comprising a casing, a fuse in said casing comprising two cooperating parts and having ignition means, said cooperating parts and ignition means being arranged within the said casing so that upon rotation or tumbling of the projectile during free flight tend to provoke the ignition movement of said parts and ignition means, safety means to prevent ignition during projecting or throwing, and a centrifugal force safety device cooperating with the two parts of the fuse to prevent premature ignition of the ignition means under the action of said rotation or tumbling of the projectile.

30. An explosive projectile according to claim 29, in which the two cooperating parts are telescopically arranged relative to each other.

31. An explosive projectile according to claim 29, in which the two cooperating parts are telescopically arranged relative to each other, and 76

in which the safety device is arranged between the two telescoping parts.

32. An explosive projectile according to claim 29, in which the safety device is in the form of 5 a coiled spring ring.

33. An explosive projectile, particularly a hand grenade according to claim 29, in which the same safety means is common to the said safety device which prevents ignition during projecting 10 or throwing and to the said centrifugal force safety device.

34. An explosive projectile, particularly a hand grenade according to claim 29, in which the said safety means preventing ignition during projecting or throwing comprises at least two safety members releasing the said cooperating 5 fuse parts in series one after the other and the safety member of said centrifugal force safety device is common to the safety member preventing ignition during projecting or throwing and finally releasing in the said series.

SALAMON LEBENSART.
